AUTOMOBILE FENDER

Virgil M. Exner, Birmingham, Mich., assignor to Chrysler Corporation, Highland Park, Mich., a corporation of Delaware

Application June 11, 1956, Serial No. 41,826

Term of patent 7 years

(Cl. D14—6)

Fig. 1 is a side elevational view of automobile fender, showing my new design;

Fig. 2 is a top plan view thereof;

Fig. 3 is a rear elevational view thereof; and

Figs. 4 and 5 are sectional views taken on the lines 4—4 and 5—5, respectively, of Fig. 1.

I claim:

The ornamental design for an automobile fender, substantially as shown.
